UNITED STATES PATENT OFFICE.

EDWARD RAU, OF ALBANY, NEW YORK.

SHOE.

SPECIFICATION forming part of Letters Patent No. 425,254, dated April 8, 1890.

Application filed January 10, 1890. Serial No. 336,551. (No model.)

To all whom it may concern:

Be it known that I, EDWARD RAU, a citizen of the United States, residing in the city and county of Albany, State of New York, 5 have invented a new and useful Ventilating-Shoe, of which the following is a specification.

My invention relates to improvements in boots and shoes; and the object of my invention is to provide a shoe so constructed that a ventilation will be given thereto from the lower portion of the shoe. I attain this object by means of the mechanism illustrated in the accompanying drawings, in which—

15 Figure 1 is a plan showing the inner sole of the shoe. Fig. 2 is a section along the line 11 of Fig. 1. Fig. 3 is a rear elevation.

Similar letters refer to similar parts throughout the several views.

20 It is a well-known fact that many people are troubled with profuse perspiring of the feet, especially when wearing heavy winter shoes or boots. In order to prevent this disagreeable and unhealthy occurrence, I have

25 provided a means for allowing a circulation of air beneath the sole of the foot. For this purpose I puncture the inner sole *c* of the shoe, forming a series of apertures *b* extending around the inner sole from the toe to the

30 heel. Along the outer edge of the inner sole the upper is attached in the usual manner, and a strip of leather *C* is secured to the inner sole around the shoe from toe to heel, and in the center of the inner sole is secured the 35 strip *C'*, extending from toe to heel, leaving a narrow groove or channel *c*, into which the holes *b* open. I cause the channel *c* to communicate with the outer surface of the shoe by means of the grooved strip *H*, attached to

40 the upper just above the heel, and provided with a longitudinal groove on the side, placed

in contact with the upper, said groove placed in connection with the channel at the heel, the grooved strip *H* being bifurcated at one end and attached to the shoe on each side of 45 the channel. As thus arranged the air will circulate through the opening in the heel-piece into the channel *c*, and from thence through the apertures *b* to the interior of the shoe. I attach the sole *D* and heel *E* in the 50 usual manner.

As thus constructed my shoe is light and flexible, and having the piece *C'* attached to the inner sole makes it unnecessary to have so heavy a shank as is usually placed in the 55 instep of a shoe. The expense of making the shoe is not augmented to any appreciable extent, and the value of the shoe to the user is greatly increased. Perspiring of the feet is avoided and the object for which the invention is made is attained.

What I claim as my invention, and desire to secure by Letters Patent, is—

In a shoe, a perforated inner sole having a narrow strip of leather *C* attached to its lower 65 surface, and extending around the sole near the edge, and also having a strip of leather *C'* placed in the center of the lower surface of said sole, extending from heel to toe, forming a channel entirely around the shoe, the perforations in said inner sole opening into the channel *c* between the two strips *C* and *C'*, with the bifurcated grooved strip *H*, attached to the outer side of the upper just above the heel, the groove in said strip *H* communicating with the channel *c*, all substantially 70 as described.

EDWARD RAU.
